UNITED STATES PATENT OFFICE.

FREDERICK E. HASTINGS, OF DEVON, ASSIGNOR TO THE A. M. COLLINS MANUFACTURING COMPANY, OF PHILADELPHIA, PENNSYLVANIA.

DESIGN FOR A CARD-MOUNT.

SPECIFICATION forming part of Design No. 24,693, dated September 24, 1895.

Application filed August 26, 1895. Serial No. 560,604. Term of patent 7 years.

To all whom it may concern:

Be it known that I, FREDERICK E. HASTINGS, a citizen of the United States, and a resident of Devon, Chester county, Pennsylvania, have 5 invented a new and original Design for a Card-Mount Border, of which the following is a specification.

My design relates to a pattern or border for a card-mount, and is shown upon an oblong 10 rectangular card. Obviously, however, the outline of the card forms no part of the design, the essential or characteristic features of which consist of a narrow band having longitudinally disposed thereon a continuous 15 scroll-like figure. One portion of the band is of greater width than the remaining portions, and in this wide portion of the band the scrolls are divided so as to inclose a panel.

a represents the card; *b*, the narrow portions of the band; *d*, the wide portion of the 20 same; *f*, the single scroll figure; *g*, the double or divided scroll figure, and *h* the inclosed panel.

I claim—

The design for a card mount, substantially 25 as described and as shown in the accompanying drawing.

In testimony whereof I have signed my name to this specification in the presence of two subscribing witnesses.

FREDERICK E. HASTINGS.
